UNITED STATES PATENT OFFICE.

WILLIAM H. ROUSTON, OF DETROIT, MICHIGAN; GRACE DURYEA ROUSTON, ADMINISTRATRIX OF SAID WILLIAM H. ROUSTON, DECEASED.

CENTRIFUGAL EXTRACTOR.

Application filed November 26, 1920. Serial No. 426,664.

To all whom it may concern:

Be it known that I, WILLIAM H. ROUSTON, citizen of the United States, residing at Detroit, county of Wayne, State of Michigan, have invented a certain new and useful Improvement in Centrifugal Extractors, and declare the following to be a full, clear, and exact description of the same, such as will enable others skilled in the art to which it pertains to make and use the same, reference being had to the accompanying drawings, which form a part of this specification.

My invention relates to improvements in extractors of the centrifugal type. The object is to provide an extractor of such type so mounted and coupled with its driving shaft that, irrespective of the carried load, whether the load be so arranged as to balance or not, the rotating basket will rotate smoothly and evenly, without wobbling motion or excessive vibration.

In the drawings,—

Figure 1 is an end elevation showing the extractor attached to the end of a washing machine.

Fig. 2 is a fragmentary sectional view of the extractor.

Fig. 3 is a section taken on the dotted section line in Fig. 2.

Let *a* indicate a washing machine of any conventional type to the end of which is attached a power-driven extractor of the centrifugal type.

b is the motor for driving the extractor; *c* is a shaft extending from the motor to a driving pulley *d*. A drive belt *e* passes over this pulley *d* and over a pair of pulleys *f*, but one of which is shown in Fig. 1, and around a flywheel *g* positioned below the extractor and mounted on a shaft *h*, which shaft extends upwardly through the bottom of the vat of the extractor, such vat being indicated as *i*, and provided with an education pipe *k*, as shown in Fig. 1. This shaft *h* is suitably mounted in ball thrust bearings *m*. *n* is the supporting shelf which extends from the end of the washer and supports the extractor vat. Fixed to the upper end of the drive shaft *h* is a cylindrical cup-shaped clutch member *o*.

The rotatably driven basket provided with perforated side wall is indicated as *p* and the bottom of the basket is axially recessed as at *p*². Disposed within this axial recess, somewhat elevated above the bottom of the

basket is a rounded supporting pivot *q* provided with an axial teat-like projection *q*². This rounded supporting pivot is of greater diameter than the diameter of the cylindrical cup-shaped clutch member *o* and is adapted to be received and supported by such cup-shaped clutch and to frictionally engage the same so that the basket will be driven thereby. The teat-like projection *q*² is adapted to be received within an axial recess *s*² formed in a stub shaft *s* carried interiorly of the cup-shaped clutch member *o*.

The extractor is so constructed that when the basket is empty it will be supported and balanced, as shown in Fig. 2, the rounded pivot *q* resting within the cup-shaped clutch *o*. If, however, the basket is loaded unevenly so as to tilt downwardly on one side this downward tilting movement will be restrained after a certain limited movement by the action of the teat *q*² in the recess *s*².

In the operation of the device, by virtue of the coupled connection made between the basket and the driving shaft, even though due to an uneven load the center of gravity of the basket does not coincide with the extension of the axis of the driving shaft, the basket will rotate without wobble and without exerting such a torque as to cause oscillation or movement of the machine over the floor upon which it rests. Owing to this form of connection the basket will find its balance when rotating irrespective of whether the load carried is arranged so as to balance the basket. The device possesses further compensating advantages in that when positioned on an uneven floor the axis of rotation of the basket may yet remain perpendicular. If the basket were rigidly secured to the driving shaft and carried an unbalanced load the same result would be produced as in the rotation of an unbalanced fly-wheel; there would be resulting wobble and oscillation and the machine would move around over the floor upon which it rested.

What I claim is:

In an extractor of the centrifugal type, the combination with a vat, of a drive-shaft extending upwardly through the bottom of the vat, a clutch member in the form of a cup-shaped hub carried at the upper end of said drive shaft, the bottom of said hub provided with an axial depression, a rotatable basket positioned within said vat and having a bottom bent upwardly axially to form a

concavity, a clutch plate secured to the bottom of the basket and extending upwardly interior the concavity and provided with a downwardly convex portion which seats 5 within the hub to form frictional engagement with the side wall thereof to be driven thereby, said convex portion provided with a

downwardly projecting axial teat-like member received within the depression in the bottom of the hub to limit the wobble of the basket during rotation. 10

In testimony whereof, I sign this specification.

WILLIAM H. ROUSTON.
